GAME APPARATUS

Filed July 26, 1924

Patented Aug. 18, 1925.

1,550,039

UNITED STATES PATENT OFFICE.

HENRY R. H. MYTTON, OF LOS ANGELES, CALIFORNIA.

GAME APPARATUS.

Application filed July 26, 1924. Serial No. 728,439.

To all whom it may concern:

Be it known that I, HENRY R. H. MYTTON, a citizen of the United States, residing at Los Angeles, in the county of Los Angeles and State of California, have invented certain new and useful Improvements in Game Apparatus, of which the following is a specification.

My invention relates to a game apparatus and has for its principal object, the provision of relatively simple means, including a game board and movable game pieces for playing a game that will, in addition to affording an interesting and pleasing pastime, serve to test the skill of the players in the projecting of the movable game pieces over the surface of the playing board.

Further objects of my invention are to construct the game board so that it may be folded into relatively small compass while not in use, or packed for storage or transportation, and to provide simple means whereby a pocket or storage chamber may be formed at one end of the folded board for the reception of the game pieces, counters and other movable and detachable parts of the apparatus.

With the foregoing and other objects in view, my invention consists in certain novel features of construction and arrangement of parts that will be hereinafter more fully described and claimed and illustrated in the accompanying drawings in which:

Fig. 1 is a top plan view of a game apparatus of my improved construction.

Fig. 2 is a longitudinal section taken on the line 2—2 of Fig. 1.

Fig. 3 is a section taken lengthwise of the game board when the same is folded for storage or transportation.

Fig. 4 is a perspective view of one of the projectable game pieces.

Fig. 5 is an enlarged cross section taken on the line 5—5 of Fig. 1.

Fig. 6 is an enlarged detail section taken on the line 6—6 of Fig. 3.

Fig. 7 is an enlarged detail section taken on the line 7—7 of Fig. 2.

Fig. 8 is a plan view of a one piece game board embodying my invention.

My improved game board is preferably formed in halves or two identical parts as illustrated in Figs. 1, 2 and 3, each part including a plate-like member 10 of quadrangular form and having a flat smooth upper surface.

These plates may be formed of any material, such as wood veneer, compressed fibre board or sheet metal and secured in any suitable manner on their upper surfaces and along their side edges and outer ends are low rails or ledges 11.

The two parts of the game board thus constructed, are connected to each other at their inner ends by hinges 12, that are preferably arranged between the inner ends of the side rails 11. Thus one part of half of the game board may be swung or folded over onto the other as illustrated in Fig. 3 and, to secure the parts when so folded, hooks 13, that are arranged on one end rail 11 may be engaged on pins 14 that project from the other end rail.

Secured in any suitable manner to the inner end of one part 10 and at a point half way between the sides thereof is a socket 15, one-half of which is adapted to project into a recess 16 in the adjacent edge of the other part 10, when the game board is open for use.

The top of socket 15 is flush with the smooth upper face of the game board and said socket is adapted to receive and support a pin 16 that serves as a mark during play of the game.

Painted, printed or stencilled on the top surface of the central portion of the game board and concentrically disposed about the pin socket 15 are circles 17, that are preferably spaced at equal distances apart and which serve as guides for determining the relative positions of the game pieces and the distances between the same and the pin 16, during play of the game.

Appearing on the surface of the game board at equal distances from pin 16 are transverse lines 18 that may be termed "dead" or "foul" lines, inasmuch as the game pieces after being projected by the players must stop or lie within the space between said lines and pin 16 in order to count or score for the respective players.

Appearing on the surface of the game board adjacent to the rails 11 at the ends of said board, are transversely disposed lines 19, that may be termed "starting" lines, inasmuch as the game pieces are placed behind or upon said lines before being struck by the fingers of the players and projected toward the mark or pin 16.

Score of the game may be kept in any suitable manner, but I prefer to provide

simple and convenient scoring means, by forming in one member of each pair of the rails 11 at the sides of members 10 a row of apertures, such as 20 and said apertures being adapted to receive markers or counting pins, such as 21.

The projectable game pieces 22 used in playing my improved game, are shaped somewhat similar to an ordinary hair pin 10 as illustrated in Fig. 4 and they are preferably formed from wire, either round or square in cross section.

The distance between the legs of the game pieces is slightly greater than the diameter 15 of the pin 16.

To provide a small storage space in one end of the apparatus when the same is folded, as illustrated in Fig. 3, notches such as 23 are formed in rails 11 at the sides of 20 one of the parts of the game board near the outer end thereof and adapted to be positioned in said notches are the ends of a strip 24. Thus when the game board is folded as illustrated in Fig. 3 and the strip is 25 positioned in the notches 23, a small pocket or chamber 25 is provided between said strip and the adjacent end rails 11 and which pocket may serve as a storage space for the game pieces 22, pin 16 and the counting 30 pins 21.

In playing a game with my improved apparatus, the board is unfolded and laid on a level support such as a table and the base of pin 16 is inserted in socket 15.

35 The players, positioned at the ends of the board place the playing pieces upon or behind the starting lines 19 with the ends of the legs of said pieces pointing toward pin 16 and, by a forward snapping movement of the finger against the base of the playing piece, the latter is forcibly projected over the surface of the board toward pin 16 with the object of "ringing" the latter, or to cause said piece to stop at a point 40 immediately adjacent or near to said pin. If one player succeeds in "ringing" the pin with a game piece, then the opponent may endeavor to so manipulate his game pieces 45 as to dislodge the "ringer" or to strike and move the latter away from the pin.

Various rules may be made to govern the 50 playing of my improved game, but in all cases the object is to "ring" the pin with hairpin-shaped game pieces or to snap or drive the same into positions as close as possible to the center pin.

The concentric circles at the center of the board have nothing to do with the scoring 55 but are provided in order to make it easier to judge the distance between the pin and playing pieces.

To entitle the playing pieces to be counted, they must be driven into the space between the "dead" or foul lines 18.

60 In Fig. 8 the game board is shown as be-

ing formed from a single piece, or without the joint and hinges at the center.

In some instances it may be found desirable to provide a small shallow box-like structure that may be readily inserted or removed from the open end of the structure when the parts of the game board are folded, as illustrated in Figure 3, and which shallow box forms a filler for the open end 70 of the structure when the same is folded as well as serving as a container for the game pieces and other small articles that are stored away between periods of use.

A game apparatus of my improved construction is comparatively simple, may be 80 easily and cheaply produced and the play upon said apparatus provides a pleasing and entertaining pastime.

It will be understood that minor changes in the size, form and construction of the 85 various parts of my improved game apparatus may be made and substituted for those herein shown and described without departing from the spirit of my invention, the scope of which is set forth in the appended claims.

I claim as my invention:

1. A game apparatus comprising a playing board having a smooth flat upper surface, a pin projecting upwardly from the 95 central portion of said board and a series of hairpin-shaped playing pieces that are adapted to be projected over the surface of the board toward said pin.

2. A game apparatus comprising a playing board having a smooth flat upper surface, a pin projecting upwardly from the central portion of said board, a series of hairpin-shaped playing pieces that are adapted to be projected over the surface of 105 the board toward said pin and the surface of said playing board being provided with a series of circles concentrically arranged about said pin and with transversely disposed starting and foul lines, the latter being arranged between said concentric circles and the ends of said playing board.

3. In a game apparatus, a playing board formed in two parts that are hinged to each other so that one part may overlie the other part, a socket secured to the inner end of one part and adapted to occupy a position between the parts when the same are open for play, a pin adapted to be seated in said socket and a series of hairpin-shaped playing pieces adapted to be projected over the surface of the playing board toward said pin.

4. In a game apparatus, a playing board formed in two parts that are hinged to each other so that one part may overlie the other part, a socket secured to the inner end of one part and adapted to occupy a position between the parts when the same are open for play, a pin adapted to be seated in said 125 socket.

socket, a series of hairpin-shaped playing pieces adapted to be projected over the surface of the playing board toward said pin and a rail adapted to be positioned between the parts of the playing board when one overlies the other, to form at one end of the folded structure, a narrow storage space.

5. In a game apparatus, the combination

with a member having a smooth flat playing surface and a pin projecting upwardly from said surface, of a series of hairpin-shaped playing pieces adapted to be projected over said surface toward said pin. 10

In testimony whereof I affix my signature.

HENRY R. H. MYTTON.
